US00D627394S

(12) **United States Design Patent**
Nakayama et al.

(10) **Patent No.:** US D627,394 S
(45) **Date of Patent:** ** Nov. 16, 2010

(54) **WHITEBOARD**

(75) Inventors: **Azumi Nakayama**, Tokyo (JP); **Koji Makita**, Tokyo (JP)

(73) Assignee: **Plus Corporation**, Tokyo (JP)

(**) Term: **14 Years**

(21) Appl. No.: **29/352,876**

(22) Filed: **Dec. 29, 2009**

(30) **Foreign Application Priority Data**

Jun. 30, 2009 (JP) 2009-014810

(51) **LOC (9) Cl.** 19-06

(52) **U.S. Cl.** D19/52

(58) **Field of Classification Search** D6/300-314, D6/332; D7/698, 699; D14/336, 371, 448; D19/52, 88; D20/10, 19, 39, 40, 41, 42; 40/358, 541, 584, 611.01; 434/408, 409, 434/415, 421, 422, 425

See application file for complete search history.
